UNITED STATES PATENT OFFICE.

ALMERON W. WICKHAM, OF NEW HAVEN, CONNECTICUT.

HEATING-DRUM.

No. 895,926.

Specification of Letters Patent.

Patented Aug. 11, 1908.

Application filed May 3, 1907. Serial No. 371,626.

To all whom it may concern:

Be it known that I, ALMERON W. WICKHAM, a citizen of the United States of America, residing at New Haven, in the county of 5 New Haven and State of Connecticut, have invented new and useful Improvements in Heating-Drums, of which the following is a specification.

This invention relates to heating drums 10 designed for the purpose of utilizing the heat from the smoke and gases of combustion from a furnace, after they have left the furnace, and before they have passed into the smoke stack.

15 One of the principal objects of the invention is to economize in the use of fuel, and to utilize all of the heat units produced by the fuel, by preventing their escape through the smoke duct and out through the chimney, 20 before the heat has been fully utilized.

In furnaces as at present constructed, the products of combustion are not fully utilized and much of the heat passes up the chimney and is dissipated in the air.

25 It is one of the principal objects of my invention to fully utilize the heat units after they have left the furnace and before they are dissipated through the chimney.

Another object of my invention is to provide simple and efficient means for utilizing the heat of the smoke and gases of combustion by passing the same through a drum or cylinder provided with a series of smoke flues, and at the same time leading a quantity of cold air into the cylinder at a point nearly coincident with the smoke inlet. The column of air is led in a zigzag course between the smoke flues, impinging on the same, the moving air following along the 35 smoke flues, and continuously ascending, while the smoke and gases of combustion continuously ascend within the tubes; the heated air issuing from the cylinder at the highest point from the cold air inlet, and at a 40 point nearly coincident with the smoke outlet which is also at the highest point from the smoke inlet, and thus to utilize the heat radiated from the surface of the flues, for heating purposes.

45 These and other objects may be attained by means of the construction illustrated in the accompanying drawings, in which:

Figure 1 is a longitudinal section of a waste heat economizer made in accordance 55 with my invention. Fig. 2 is a vertical section on the line 2—2, Fig. 1. Fig. 3 is a simi-

lar section on the line 3—3, Fig. 1. Fig. 4 is a plan view of the ash deflector.

Referring to the drawing for a more particular description of my invention, the numeral 1 designates a horizontally disposed cylinder provided with partitions 2, horizontally disposed flues 3 secured at their ends to the partitions 2 and removable heads 4 at the opposite ends of the cylinder. A smoke inlet pipe 5 communicates with a smoke chamber 6 and a partition 7 separates the chamber 6 from the chamber 6^c. Depending from the inlet pipe 5 is an ash clean-out pocket 5^a provided with suitable removable receptacles 6^a for cleaning out the ashes. An ash deflector 7^a comprising a plate provided with apertures 8^a and oppositely arranged inclined deflectors 9^a extend through the top of the pipe 5 and is provided with extending arms 10^a which are designed to be struck by a suitable implement to deposit the ashes which may collect about the deflector into the receptacles 6^a. A cold air pipe 8 communicates with the cylinder at a point near the smoke inlet pipe 5, said cold air pipe extending downward from the cylinder 1. Horizontally disposed deflector plates 9 extend from the partitions 2 and terminate at a short distance from the partition 80 at opposite ends, as shown in Fig. 1. The heated smoke entering the pipe 5 passes the ash deflector through the apertures 8^a into the smoke chamber 6, and through the lower flues 3 to the smoke chamber 6^b at the opposite end of the cylinder, and from thence passes back through the intermediate series of flues to the smoke chamber 6^c from which the smoke is led through the upper series of flues to the smoke chamber 6^d. In the upper series 85 of flues 3 at the end adjacent to the smoke chamber 6^d a series of retarders or bushings 6^e are provided, these bushings serving to reduce the bore of the flues 3 at the outlet ends to retard the heat and extract all of the heat units 90 therefrom before it escapes into the chamber 6^d and out through the outlet pipe 10. In the outlet pipe 10 I have provided a suitable check draft or damper 10^c. The cold air entering 95 the pipe 8 and the smoke and heated gases entering through the pipe 5 into the chamber 6 are carried in a zigzag course from the bottom lower corner of the cylinder to the diagonally opposite upper corner of the cylinder, 100 the air being heated in its course through the cylinder by the hot air and gases in the flues 3, and the heated air being led out through 105 110

the pipe 10 to registers or to be utilized in any suitable manner, while the smoke passes out through the outlet 12.

From the foregoing it will be obvious that 5 a heat economizer made in accordance with my invention will thoroughly utilize the heat from the smoke and gases of combustion before they pass up through the chimney, and that a material saving in fuel results from 10 this method of treatment.

My invention may be made at comparatively slight cost, occupies but little space, and thoroughly utilizes the heat units which are wasted in the ordinary furnace.

15 By means of the bushings in the end of the tubes, the area of all the openings therein shall be made no greater than the area of the smoke pipe inlet at bottom of heater, and the gases of combustion are expanded within the 20 tubes to several times their volume at the entrance from the furnace to heater, thus causing a retarding of the flow and imparting heat to the air surrounding and flowing alongside the outside of the tubes.

25 Having thus described the invention, what I claim is:

1. A heating drum comprising a horizontal casing having a compartment at each end thereof, a plurality of series of flues communicating at their opposite ends with said compartments, partitions in said compartments, whereby the products of combustion are compelled to take a circuitous path in a zig 30 zag course through the bottom series of flues back through the intermediate series of flues, a smoke inlet at one end of the casing, a cold air inlet adjacent to the smoke inlet and a series of deflectors dividing the flues into series 35 and compelling the air to take a zig zag course parallel with the path of movement of the products of combustion, and retarders for restricting the outlet passages in the outer ends of the upper series of flues.

35 flues back through the intermediate series of flues and outward through the upper series of flues, a smoke inlet at one end of the casing, a cold air inlet adjacent to the smoke inlet and a series of deflectors dividing the flues

into series and compelling the air to take a 40 zig zag course parallel with the path of movement of the products of combustion.

2. A heating drum comprising a horizontal casing having a compartment at each end thereof, a plurality of series of flues communicating at their opposite ends with said compartments, partitions in said compartments, whereby the products of combustion are compelled to take a circuitous path in a zig 45 zag course through the bottom series of flues 50 back through the intermediate series of flues and outward through the upper series of flues, a smoke inlet at one end of the casing, a cold air inlet adjacent to the smoke inlet and a series of deflectors dividing the flues into series 55 and compelling the air to take a zig zag course parallel with the path of movement of the products of combustion, and retarders for restricting the outlet passages in the outer ends of the upper series of flues.

3. A heating drum comprising a horizontally disposed cylinder, heads within said cylinder, flues extending through said heads, smoke chambers formed outside the heads, partitions in said smoke chambers, deflectors 60 extending in opposite directions in the flue chamber, a smoke inlet pipe, and a cold air inlet pipe located in juxtaposition at the lower corner of the cylinder, and a hot air outlet located at the opposite upper corner 70 from the inlet pipe.

In testimony whereof, I affix my signature in presence of two witnesses.

ALMERON W. WICKHAM.
